Joe A. Hughtlett

C. Snow & Co.

UNITED STATES PATENT OFFICE.

JOE A. HUGHLETT, OF FULTON, KENTUCKY.

WAGON-BED RAISER.

SPECIFICATION forming part of Letters Patent No. 416,059, dated November 26, 1889.

Application filed May 25, 1889. Serial No. 312,022. (No model.)

To all whom it may concern:

Be it known that I, JOE A. HUGHLETT, a citizen of the United States, residing at Fulton, in the county of Fulton and State of Kentucky, have invented a new and useful 5 Wagon-Bed Raiser, of which the following is a specification.

My invention relates to improvements in wagon-bed raisers; and it consists in certain 10 novel features hereinafter described and claimed.

In the accompanying drawings, Figure 1 is a perspective view of an apparatus embodying my invention. Fig. 2 is a vertical transverse section, and Fig. 3 is a detail longitudinal section. Fig. 4 is a detail in side elevation of the gravity-pawl.

In carrying out my invention I employ a frame A, consisting of the side bars B B and 20 the end bars C C, which is secured to any suitable fixed support. This frame A is provided at its ends with the pulleys or rollers D D, over which the hoisting-rope passes, and on the upper side of the side bars I secure

25 the journal-boxes E E, in which the ends of the windlass-shaft are mounted. The windlass F is formed integral with its shaft or secured rigidly thereto, and is provided at one end with the ratchet-disk G, as clearly shown.

30 Adjacent to this ratchet-disk G, I loosely mount on the windlass-shaft the operating-lever H, and on the operating-lever H is pivoted a pawl I, which engages the said ratchet-disk G. This pawl is normally thrown into

35 engagement with the said ratchet-disk by the spring J, arranged between the said pawl and a fixed stop on the lever; and the pawl is disengaged from the ratchet-disk by an angle-lever K, pivoted on the operating-lever near 40 its outer end and connected with the pawl by a rod L, as shown.

The windlass-shaft is provided near its end with the notched disk or collar M, rigid upon the shaft, and said collar is engaged by a 45 gravity-pawl N, pivoted on the frame and having a shoulder O, which is adapted to engage the notches of the said collar or disk. This gravity-pawl prevents backward movement of the windlass after the body has been

raised, and, in order that it may be disengaged 50 from the collar or disk, when so desired, I provide a button P, which is somewhat stiffly pivoted on the side of the pawl and adapted to be turned so as to throw it above or below the shoulder O. When thrown above the 55 shoulder O, which is, in fact, its normal position, this shoulder meshes with the notched collar, and when thrown below the button rides over the faces of the teeth of the collar and elevates the shoulder out of contact. 60

The hoisting-ropes Q are secured to the windlass and pass therefrom over the rollers or pulleys D, and are adapted to pass around the ends of the wagon-body R and beneath the same. When it is desired to raise a 65 wagon-body, the ends of the hoisting-ropes are passed under the ends of the wagon-body, the operating-lever is then reciprocated so as to rotate the windlass and thereby wind the ropes thereon, and consequently raise the 70 body.

My device is very cheap and simple and its advantages are thought to be obvious.

When it is desired to lower the wagon-body, the button P is turned downward below 75 the shoulder, as shown in Fig. 3, so as to rest upon a tooth of the disk M. It only now remains to intermittently withdraw the pawl I from mesh with the ratchet-wheel G and permit the same to turn a few teeth at a 80 time.

Having thus described my invention, what I claim, and desire to secure by Letters Patent, is—

1. The combination of the frame, the windlass mounted thereon, the ratchet-disk, the operating-lever loosely mounted on the windlass-shaft adjacent to the said disk, a pawl pivoted on said lever and engaging said disk, the notched collar or disk rigidly secured on 85 the windlass-shaft, the gravity-pawl pivoted on the frame and having a shoulder engaging said notched disk or collar, and the button pivotally mounted on said gravity-pawl, as 90 set forth. 95

2. The combination of the frame, the windlass mounted thereon, the ratchet-disk upon the windlass-shaft, the operating-lever piv-

oted on the shaft, a pawl mounted on the lever and engaging the ratchet, means for disengaging the pawl, a notched collar mounted on the shaft, a gravity holding-pawl piv-
5 oted to the frame and engaging the collar, and means for elevating the pawl from contact with the collar, substantially as specified.

In testimony that I claim the foregoing as my own I have hereto affixed my signature in presence of two witnesses.

JOE A. HUGHLETT.

In presence of—
T. M. HUGHLETT,
T. B. SELLARS.
